US00D914007S

(12) **United States Design Patent** (10) Patent No.: **US D914,007 S**
(45) Date of Patent: **** Mar. 23, 2021**

(54) **CASE FOR ELECTRONIC
COMMUNICATIONS DEVICE**

(71) Applicant: **SPIGEN KOREA CO., LTD.**, Seoul (KR)

(72) Inventor: **Tae Sung Yoon**, Seoul (KR)

(73) Assignee: **SPIGEN KOREA CO., LTD.**, Seoul (KR)

(**) Term: **15 Years**

(21) Appl. No.: **29/732,919**

(22) Filed: **Apr. 28, 2020**

(51) LOC (13) Cl. **14-03**

(52) U.S. Cl.

USPC **D14/250**

(58) **Field of Classification Search**

CLAIM

The ornamental design for a case for electronic communications device, as shown and described.

DESCRIPTION

FIG. 1 is a front perspective view of a case for electronic communications device showing a first embodiment of my new design;

FIG. 2 is a rear perspective view thereof;

FIG. 3 is a front elevational view thereof;

FIG. 4 is a rear elevational view thereof;

FIG. 5 is a left side elevational view thereof; FIG. 6 is a right side elevational view thereof; FIG. 7 is a top plan view thereof; FIG. 8 is a bottom plan view thereof; FIG. 9 is a rear perspective view thereof showing the rear storage compartment cover portion of the case in an open position;

FIG. 10 is an enlarged detail view of the encircled region of FIG. 2; FIG. 11 is an enlarged detail view of the encircled region of FIG. 5;

FIG. 12 is a front perspective view of a case for electronic communications device showing a second embodiment of my new design; FIG. 13 is a rear perspective view thereof; FIG. 14 is a front elevational view thereof; FIG. 15 is a rear elevational view thereof; FIG. 16 is a left side elevational view thereof; FIG. 17 is a right side elevational view thereof; FIG. 18 is a top plan view thereof; FIG. 19 is a bottom plan view thereof;

FIG. 20 is a rear perspective view thereof showing the rear storage compartment cover portion of the case in an open position; FIG. 21 is an enlarged detail view of the encircled region of FIG. 13; FIG. 22 is an enlarged detail view of the encircled region of FIG. 16;

FIG. 23 is a front perspective view of a case for electronic communications device showing a third embodiment of my new design; FIG. 24 is a rear perspective view thereof; FIG. 25 is a front elevational view thereof; FIG. 26 is a rear elevational view thereof; FIG. 27 is a left side elevational view thereof; FIG. 28 is a right side elevational view thereof; FIG. 29 is a top plan view thereof; FIG. 30 is a bottom plan view thereof;

FIG. 31 is a rear perspective view thereof showing the rear storage compartment cover portion of the case in an open position; FIG. 32 is an enlarged detail view of the encircled region of FIG. 24; and, FIG. 33 is an enlarged detail view of the encircled region of FIG. 27.

The dot-dash broken line circles in FIGS. 2, 5, 13, 16, 24, and 27 delineate portions of the case for electronic communications device that are part of the claimed design and are shown on an enlarged scale in FIGS. 10, 11, 21, 22, 32, and 33.

The dashed broken lines throughout the drawing figures depict portions of the case for electronic communications device that form no part of the claimed design.
